UNITED STATES PATENT OFFICE.

WILLIAM YEOCUM, OF DALLAS CITY, ILLINOIS, ASSIGNOR TO STAR CEMENT BLOCK MACHINE COMPANY, OF DALLAS CITY, ILLINOIS.

BRICK-MACHINE.

1,102,708.

Specification of Letters Patent.

Patented July 7, 1914.

Application filed June 27, 1910. Serial No. 569,193.

To all whom it may concern:

Be it known that I, WILLIAM YEOCUM, a citizen of the United States, residing at Dallas City, in the county of Hancock and State 5 of Illinois, have invented a new and useful Brick-Machine, of which the following is a specification.

This invention relates to brick machines such as are adapted particularly for use in 10 the manufacture of cement or concrete bricks, although the device of the present invention can be used in other connections and for other purposes if desired.

The principal objects of the invention are 15 to improve and simplify the construction of brick machines as well as to increase their efficiency in use and to decrease the expense attending their manufacture and operation.

A further object of the invention is to 20 provide a brick machine having improved means for forming a plurality of mold compartments above a common pallet and for easily and quickly removing the walls of said mold compartments from said pallet 25 after the bricks have been molded.

With the foregoing and other objects in view which will appear as the description proceeds, the invention resides in the combination and arrangement of parts and in 30 the details of construction hereinafter described and claimed, it being understood that changes in the precise embodiment of invention herein disclosed can be made within the scope of the claim without departing 35 from the spirit of the invention.

In the accompanying drawings forming part of this specification, Figure 1 is a vertical section on the line 1—1 of Fig. 3. Fig. 2 is a front elevation of the machine, partly 40 broken away. Fig. 3 is a plan view of the machine. Fig. 4 is a detail section on the line 4—4 of Fig. 1, taken at one side of the machine.

Like reference numerals indicate corresponding parts in the different figures of the drawings.

The brick machine of the present invention is constructed with a suitable frame which preferably includes pairs of supporting legs 1—1 and 2—2. The legs of each pair are connected by a cross piece 3. Extending from the cross piece 3 on one side of the machine to the cross piece 3 on the other side of the machine is a connecting member 4 to 55 which is secured by means of a bolt 5 the

lower end 6 of a pair of diagonally extending brace rods 7 and 8 which are secured at their upper ends in any suitable manner to the upper ends of the legs 1 and 2. Bolted or otherwise suitably secured at 9 to the 60 upper ends of the legs 1 and 2 is a pair of angle iron sills 10. The angle irons 10, as shown best in Fig. 1, extend some distance rearwardly of the machine so as to produce an overhanging portion. At their rear ends, 65 the angle irons 10 serve to support a transversely extending angle iron cross bar 11 which is held in position upon the angle irons 10 by adjusting members such as the bolts 12 each provided with a lower spacing 70 nut 13 and an upper spacing nut 14, a third nut 15 being disposed below the upper flange of the angle irons 10 to hold the transverse angle iron 11 properly in position upon the angle irons 10. 75

Supported upon the forward ends of the angle irons 10 and extending transversely of the machine is a table 16. The table 16 is intended to support a transversely extending pallet or board 17 having a metal plate 18 secured on the upper surface thereof. Extending along the front edge of the pallet 17 is a swinging member 19 which is pivoted at 20', as shown in Fig. 3 at one of the forward corners of the table 16 and is adapted 80 to swing forward into the dotted line position shown in Fig. 3 for the purpose of opening the mold compartment as herein-after described. The swinging member 19 is of approximately the same height as the 90 pallet 17 and has secured thereon a plurality of gates 21 each of which is adapted to close the forward end of one of the mold compartments as shown in Fig. 3. The end gates 20 are secured on the swinging member 95 19 by means such as the plates 21 and the bolts 22 and 23, the bolts 22 extending through the plates 21 and gates 20 and the bolts 23 extending through the plates 21 and swinging member 19. The different gate 100 members 20 are separated from each other by distances sufficient to permit the sliding side walls 24 of the mold compartments, as shown in Figs. 2 and 3, to slide therebetween.

When the side walls 24 of the mold compartments are slid forward from the dotted line position so that they project at their forward ends between the gates 20, the mold compartments are closed and are adapted to receive the cement which is to be molded, 110

and after the articles have been molded, the side walls 24 are slid backward to the dotted line position in Fig. 3 and the front gates 20 are swung open to the dotted line position in Fig. 3 so as to permit the pallet 17 to be removed together with the molded bricks thereon and a new pallet substituted preparatory to the next molding operation.

The rear ends of the mold compartments, as shown in Fig. 1, are closed by fixed walls 26 which rest at their lower ends upon the table 16 just in front of a cross piece 27 which extends entirely across the machine and is bolted or otherwise secured at 28 to the angle iron 10. The cross piece 27 thus serves to hold both the table 16 and the fixed end walls 26 securely in position. The different fixed walls 26 are spaced away from each other sufficiently to permit the side walls 24 of the mold compartments to slide therebetween. The fixed end gates 26 of the different mold compartments are braced at their upper ends by a transversely extending cross piece 29 which is provided with a plurality of downwardly extending bolts 30 each connecting with the upper end of one of the end gates 26 so as to brace the same. The stationary cross piece 29 engages the upper edges of the sliding walls 24 and serves to guide the same. The cross piece 29 is secured by means of the bolts 31 to the cross piece 27.

The different sliding walls 24 are rigidly connected with each other adjacent their rear ends by means of a transversely threaded rod 35 having thereon pairs of nuts 36 arranged on opposite sides of the sliding members 24 so as to space them properly apart. By adjusting the nuts 36 upon the rod 35 the distance between the walls 24 can be properly proportioned. In addition to the cross rods 35, the walls 24 are connected with each other by a flat cross piece 37 which extends across the upper edges of the walls 24 and is bolted to said walls so as to be movable therewith. Between each pair of walls 24, the cross piece 37 has secured thereto by means such as the bolts 38 a short angle iron 39 one of which is shown in Fig. 1. Each of the angle irons 39 projects downwardly between a pair of the sliding walls 24 and spaces them properly apart. The means for securing the cross piece 37 to the sliding walls 24 is best shown in Fig. 4 and consists of one or more bolts 40 secured at their lower ends to cross pieces 41 which fit against the lower edges of two or more of the sliding walls 24. By tightening the bolts 40 the cross piece 37 is drawn tightly against the upper edges of the walls 24 and the cross pieces 41 are drawn tightly against the lower edges thereof.

For the purpose of guiding the sliding walls 24 in their backward and forward movement, each of the two outer walls 24 as

shown in Fig. 4 has bolted thereto a longitudinally extending strip or rib 42 held in place by the bolt or rivet 43. The strips 42 are engaged by horizontally disposed plates or guides 44 shown in Figs. 3 and 4. The plates 44 are secured at their rear ends by means of the bolts 12 to the rear angle iron 11, suitable spacing members 45 being interposed between the upper flange of the angle iron 11 and the plates 44 as shown in Fig. 4. The strips 42 slide beneath the plates 44 during the forward and backward sliding movement of the walls 24.

The means for sliding the walls 24 into and out of position preferably consists of an operating handle 47 secured on a rock shaft 48 which is journaled in the framework of the machine. The rock shaft 48 is provided with a pair of upwardly extending arms 49 each of which extends between a pair of studs 50 mounted in one of the sliding walls 24. When the handle lever 47 is thrown forward, the arms 49 simultaneously slide all of the walls 24 forward, and when the lever 47 is thrown rearwardly the walls 24 are simultaneously thrown rearwardly to the dotted line position indicated in Figs. 1 and 3 of the drawings.

It will be observed from Fig. 1 that the rear stud 50 is disposed in a lower horizontal plane than the forward stud 50, whereby to permit the rocking frame 41 to be swung to its rearmost position without binding.

The machine preferably is used as follows. While the walls 24 are drawn rearwardly into open position as indicated by the dotted lines in Fig. 3 and the wall 19 is opened as wide as desired, the pallet 17 is inserted in position with its rear edge abutting against the fixed walls 26 which form the rear ends of the mold compartments. The swinging member 19 carrying the front walls or gates 20 of the mold compartments, is then swung in closed position, being locked in such position by means of any suitable form of catch such for example as the spring catch 52 indicated in Fig. 1 of the drawings, said catch being secured to the bottom of the table 16 and having an upward projection adapted to pass through the table and into a socket in the lower end of the swinging member 19, said catch being operated by means of a knob or handle 53. After the front gates 20 are closed, the handle 47 is operated to draw the side members 24 forward, these members sliding between the fixed rear walls 26 and between the forward walls 20 so as to produce a plurality of mold compartments as illustrated in Fig. 3. The cement or other material is then inserted into these compartments and suitably tamped or troweled off. After the molded material has become sufficiently set, the lever 47 is operated to withdraw the sliding walls 24 into the dotted line position. The

130

swinging member 19 is then unlocked and swung into open position, after which the pallet 17 on which the different molded articles are standing, can be removed from the 5 machine and a new pallet substituted so as to permit the molding operation to be repeated in the manner described.

What is claimed is:

In a brick making machine, a frame; sills 10 mounted on the frame; a table mounted on the sills; a pallet supported on the table; a gate bar pivoted to the table and resting on the same for horizontal swinging movement to align the upper edge of the gate bar with the 15 upper face of the pallet; a set of spaced end walls secured to the gate bar; a set of fixed, spaced end walls coöperating with the pallet; connected inner and outer side walls mounted to slide across the pallet and across

the gate bar between the walls of the respective sets; ribs secured to the outer side walls; guides overhanging the ribs; a cross bar disposed above the sills and constituting a support for the slideable side walls; and adjusting members connected with the sills and 25 with the cross bar to effect a raising and lowering of the cross bar thereby to level the slideable side walls with respect to the pallet and the gate bar, the guides being retained by the adjusting members.

In testimony that I claim the foregoing as my own, I have hereto affixed my signature in the presence of two witnesses.

WILLIAM YEOCUM.
